(57) **CLAIM**

The ornamental design for a beam frame for bumper back beam of vehicle as shown and described.

DESCRIPTION

FIG. 1 is a perspective view of a beam frame for bumper back beam of vehicle showing our new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a right side elevational view thereof, the left side elevational view being a mirror image thereof; and,
FIG. 7 is a reference view showing a bended bumper back beam of the vehicle according to an embodiment of the new design.

The broken lines in the drawings represent environmental structure which form no part of the claimed design. The dash-dot-dash broken lines at the left end side thereof define the boundaries of the claimed design and form no part thereof.
